UNITED STATES PATENT OFFICE.

GEORGE S. STRONG, OF PHILADELPHIA, PENNSYLVANIA.

STEAM-BOILER.

SPECIFICATION forming part of Letters Patent No. 315,974, dated April 14, 1885.

Application filed November 4, 1884. (No model.)

To all whom it may concern:

Be it known that I, GEORGE S. STRONG, a citizen of the United States, residing in Philadelphia, Pennsylvania, have invented certain 5 Improvements in Steam-Boilers, of which the following is a specification.

My invention consists of certain improvements, fully described and claimed hereinafter, in the construction of the steam-boiler for 10 which Letters Patent No. 266,551 were granted to me October 24, 1882.

In the accompanying drawings, Figure 1, Sheet 1, is a sectional plan view of a steam-boiler made according to my improvements; 15 Fig. 2, Sheet 2, a perspective view, drawn to a reduced scale, of the outer shell of the boiler; Fig. 3, a perspective view of the inner shell of the fire-boxes and combustion-chamber; Fig. 4, Sheet 3, perspective views of the plates used in carrying out part of my improvements; 20 Fig. 5, Sheet 3, perspective views of modified forms of the plates shown in Fig. 4; Fig. 6, Sheet 4, views of plates which may be used in constructing the outer shell of the boiler; and 25 Figs. 7, 8, 9, and 10, Sheet 4, views illustrating the mode of constructing the outer shells of the fire-boxes.

Referring to Figs. 1, 2, and 3, A and A' are the outer shells of the two fire-boxes; B, the 30 barrel of the boiler, and D the shell of the smoke-box, E E' being the two corrugated inner shells of the fire-box; F, the corrugated shell of the combustion-chamber; G, one tube-sheet; G', the opposite tube-sheet, and H the system of tubes.

As regards general arrangement, the above-mentioned parts are the same as those described in the above-mentioned patent. Two of the features of my present invention relate to 40 the parts where the two inner corrugated shells of the fire-box merge into the shell of the combustion-chamber, and the part where two outer shells of the fire-box merge into the shell of the barrel B of the boiler. In my former patent each inner shell of the fire-box had a rounded end and was connected with the rounded end of the shell of the combustion-chamber by a short tube. I discard this plan for the more substantial and safe connection, which 45 I will proceed to explain.

I make that portion of the boiler which con-

nects the two inner shells, E E', of the fire-box—that is, the portion between the dotted lines x and y in Figs. 1 and 4—in the manner which can be best described in connection with 55 the perspective views, Fig. 4, Sheet 3. The connection consists of three plates—namely, the central or gusset plate, H', and the two side plates, I I'—all shaped by pressure between dies. The central plate, H', has two 60 semicircular ends, a a', the former being made to project into or overlap one half, or thereabout, of the circular end of the inner shell, E, of the fire-box, and the latter to project into or overlap one half, or thereabout, of the 65 circular end of the other inner shell, E', of the fire-box, the end b of the side plate I being made to project into or overlap the other half of the end of the shell E, and the end b' of the side plate I' to project into or overlap the 70 other half of the shell E'. The opposite semicircular end, d, of the side plate I is formed to project into or overlap one half of the circular end e of the shell F of the combustion-chamber, and the semicircular end d' of the 75 side plate I' projects into or overlaps the other half of the said circular end of the shell F of the combustion-chamber. The inclined edges f and h of the central gusset-plate, H', coincide respectively with the edges f' and h' of 80 the side plate I, and the edges m and n of the gusset-plate with the edges m' and n' of the side plate I'.

As regards the junction of the several plates H', I, and I' with each other, I prefer to make 85 them with butt-joints and to connect them together by means of inner and outer strips and rivets in a well-known manner, the side plates, I I', being riveted directly at one end to the shell of the combustion-chamber, and at the 90 opposite ends to the shell of the fire-box, to which are also secured the two semicircular ends of the gusset-plate H'.

A slightly-different arrangement of connecting-plates is shown in the diagram, Fig. 5. 95

I prefer in all cases to corrugate the side plates, I I', as shown in Figs. 1 and 3.

As regards the connection of the outer shells of the fire-box with the barrel of the boiler, precisely the same plates may be employed as 100 those described above, or two die-pressed connecting-plates, W W', (which will be readily

(No Model.)
